UNITED STATES PATENT OFFICE.

HUDSON F. STORY, OF HIGHLAND, CALIFORNIA, ASSIGNOR OF ONE-HALF TO JOHN D. BOLEY, OF HIGHLAND, CALIFORNIA.

PUMP-HEAD.

1,154,348.

Specification of Letters Patent. Patented Sept. 21, 1915.

Application filed July 16, 1913. Serial No. 779,395.

To all whom it may concern:

Be it known that I, HUDSON F. STORY, a citizen of the United States, residing at Highland, in the county of San Bernardino and State of California, have invented a new and useful Pump-Head, of which the following is a specification.

This invention relates to that class of pump-heads such as is shown, for example, in my previous invention for improvements in pump-heads, patented February 16, 1909, No. 912,984, and is designed to cause a continuous upward movement of the column of fluid in the pump-stock and is adapted to operate superposed pistons.

An object of this invention as in said former one is to effect successive lifting movements of the pistons by novel means whereby the load from one piston will be taken up by the other piston smoothly and without jar while the column of fluid is moving upward, and without any pulsation and variation in force of the stream that issues from the pump.

In contradistinction to said former invention, an object is to effect a more copious flow.

Another object is to effect the foregoing results by a simpler device than that shown in said previous patent.

In said former invention I provide two cams of similar construction arranged reversely on a common shaft, the working faces of the cams being arranged horizontally so as to act directly on the sucker rod frames to reciprocate them. By this construction the length of the strokes of the sucker rods depended upon the thrust of the cams and it is evident that such stroke would be governed more or less by the diameters of the cams and that to get a longer stroke a larger cam would be necessary.

Generally stated, this invention differs from said former invention in the provision of a single cam arranged to act upon diametrically opposite cross heads working at right angles to the sucker rods and connected to the sucker rods by bell-crank levers. By this construction and arrangement I am enabled to obtain a larger number of strokes per minute and a greater length of piston stroke without materially increasing the diameter of the cam over the diameter of the cam in said former patent.

In said former patent the superior cusps

of the cams were diametrically opposite one another and bisected by a common axial plane, and the inferior cusps were also diametrically opposite one another and bisected by said common plane, whereas in this present invention the superior and inferior cusps are not diametrically opposite one another but are offset and bisected by different axial planes of the cams. During one complete cycle, in which the cam turns once, the lower piston will be lifted quickly against the weight of the upwardly moving column of fluid while the upper piston is making a slower movement at the end of its upstroke. Then the lower piston continues on its upstroke at substantially the same rate of speed and the upper piston reverses and gradually increases in speed until it reaches approximately the middle of its down stroke and from there decreases in speed to the end of its down stroke, at which time the lower piston has still some movement to make at the end of its upstroke. Then the upper piston reverses and makes its lifting stroke the same as just described for the lower piston.

The novel construction of the cam and other parts effects other advantages which will appear from inspection of the drawings and subjoined detail description.

The accompanying drawings illustrate the invention.

Figure 1 is a perspective view of a pump-head built in accordance with this invention. The upper sucker rod cross-head is shown at the end of its upstroke and the lower sucker rod cross-head before reaching the end of its down stroke. Fig. 2 is a plan view of Fig. 1, with the addition of a driving pulley, the cam being turned through 180° and the other operating parts being shown to correspond. Fig. 3 is an elevation mainly in section on line indicated by x^3 , Fig. 2. Fig. 4 is a vertical cross section on line indicated by x^4 , Fig. 3. Fig. 5 is an enlarged sectional detail on line indicated by x^5 , Fig. 2. Fig. 6 is an enlarged sectional plan detail on line indicated by x^6 , Fig. 3. Fig. 7 is an enlarged sectional plan detail on line indicated by x^7 , Fig. 3. Fig. 8 is an analytical, diagrammatic view of the cam and sucker rods.

An inner sucker rod 1 and an outer tubular sucker rod 2 surrounding the inner sucker rod are provided for attachment to

superposed pistons, not shown, of any well-known or preferred construction such as are well-known in the art.

The outer sucker rod 2 is fastened to a 5 stuffing box forming a slide 3 through which the inner sucker rod 1 extends and to which is pivoted a pair of connecting links 4 that are pivoted at 5 to a lower bell-crank lever 6 journaled at 7 to a suitable support as a 10 frame 8; and the inner sucker rod is fixed to an upper slide 9 to which is pivoted a pair of connecting links 10 that are pivoted at 11 to an upper bell-crank lever 12 journaled at 13 to the frame 8. The bell-crank levers 6, 15 12 are superposed and work in a common plane.

The sucker rod slides 3 and 9 are superposed and reciprocatably engage a pair of vertical slide rods 14 which are supported 20 below by any suitable means, not shown, and which are supported above by a bracket 15 carried by the frame 8.

The lower bell-crank lever 6 is pivoted at 16 to a lower connecting rod 17 which is 25 pivoted at 18 to a front, lower, horizontally working cross-head 19 that is provided at its center with a beveled roller 20 and that is adjustably connected by shouldered bolts 21 to a rear cross-head 22 provided at its center with a beveled roller 23; and the upper bell-crank lever 12 is pivoted at 24 to an upper connecting rod 25 which is pivoted at 26 to an upper, front, horizontally working cross-head 27 that is provided at its center 30 with a beveled roller 28 and that is adjustably connected by shouldered bolts 29 to an upper rear cross-head 30 provided at its center with a beveled roller 31.

The shouldered bolts 21, 29 are provided 40 with washers 32 and afford means to adjust the cross-heads 19, 22 and 28, 30, respectively, toward one another to compensate for wear.

The ends of the lower cross-heads 19, 22 45 reciprocatably engage a pair of lower, slotted, horizontal, complementary guides 33, 34 of the frame 8 and the ends of the upper cross-heads 27, 30 reciprocatably engage a pair of upper, slotted, horizontal, complementary guides 35, 36 of the frame 8, the guide 35 in this instance being detachably fastened by bolts 37 or the like.

The pair of spaced apart rollers 20, 23 55 are diametrically opposite one another and the pair of spaced apart rollers 28, 31 are diametrically opposite one another and all are in the working plane of the bell-crank levers 6, 12 and the rollers of each pair receive between their beveled faces the 60 reversely beveled front and rear faces of a cam 38 which is fastened by a key 39 and set screws 40 to a longitudinally extending shaft 41 that is journaled in front and rear boxes 42, 43 of the frame 8.

65 From the foregoing construction it is

clear that the cross-heads 19, 27 and 22, 30 are arranged diametrically opposite one another in a common plane and in the axial vertical plane of the cam 38 and that each of the sucker rods 14 is in said vertical axial plane, and that such construction effects great strength and simplicity of the working parts and provides for the application of power so as to get the full benefit of said power without liability of straining and breaking said parts.

The cam shaft 41 may be driven by any suitable means and in this instance I have shown a pulley 44 for this purpose as there is little, if any, variation in the load and the 80 operation is so smooth that a belt and pulley may be used where other devices of this kind employ gear wheels which of course are more expensive.

Particular attention is called to the unique 85 construction of the cam 38 which is provided with superior and inferior cusps 45, 46 that engage the rollers of the lower and upper cross-heads 19, 22 and 27, 30 respectively at different periods of time, said 90 cusps being bisected by different axial planes of the cam.

The cam 38 is provided between the superior and inferior cusps 45, 46 for 180° of its diameter with an upstroke, constant 95 speed, load-lifting limb 47 and for less than 180° of its diameter with a downstroke returning limb extending from the superior cusp substantially half way to the inferior cusp in an accelerating limb 48 and extending 100 from thence to the inferior cusp in a slowing limb 49; and the cam is provided at the inferior cusp adjacent the slowing limb with a rest face 50; and the cam is provided with an upstroke valve-closing limb 51 extending 105 from the rest face to the lifting limb 47. It is thus seen that the entire downstroke limb, rest face and upstroke valve-closing limb 48, 49, 50, 51 take up 180° of the cam diameter.

The rim of the cam for the greater part of its circumference is much narrower than the space between the rollers 20, 23 and rollers 28, 31 respectively so that the front rollers 20, 28 ordinarily act as idlers only 115 but the rim is thickened at the superior cusp 45 to substantially the widths of said space to form a reversing face 52 and the rim is also thickened to the same extent at the inferior cusp 46 to form a node 53 which prevents any upward movement of the cross-heads while the rest face 50 engages the rear roller 28 or 31 as the case may be.

From the foregoing it is clear that in practical operation as clearly shown in Fig. 125 8, considering the lower sucker rod slide 3 in the bottom position a^1 of its downstroke with the cam 38 turned to bring the rollers 20, 23 in the position designated a^1 , when the cam is turned in the direction of the 130

feathered arrows thereon, the lower roller 23 will traverse the upstroke valve-closing limb 51 from a^1 to a^2 to lift the lower slide 3 from a^1 to a^2 while the upper roller 31 traverses the upstroke lifting limb 47 from b^1 to b^2 to lift the upper slide 9 from b^1 to b^2 ; and the lower and upper rollers and lower and upper slides will continue in operation through successive positions designated a^3 , 10 a^4 and b^3 , b^4 to a^1 and b^1 , by the end of which movements the cam will have made one complete revolution and both the lower and upper slides will have been operated on an upstroke and a down stroke.

15 I claim:—

1. The combination with two sucker rods, of a shaft provided with a cam having a superior cusp and an inferior cusp and having a load-lifting limb between the superior, 20 and inferior cusps for 180° of its diameter, said cam being provided with a returning limb extending from the superior cusp substantially half way to the inferior cusp in an accelerating limb and extending from thence to the inferior cusp in a slowing limb, said cam being provided at the inferior cusp adjacent the slowing limb with a rest face, and said cam being provided with an upstroke valve-closing limb extending from the

rest face to the lifting limb; and means operably connecting the cam to said sucker rods.

2. The combination with two sucker rods, of a shaft provided with a cam having a superior cusp and an inferior cusp and having a load-lifting limb between the superior and inferior cusps for 180° of its diameter, 35 said cam being provided with a returning limb extending from the superior cusp substantially half way to the inferior cusp in an accelerating limb and extending from thence to the inferior cusp in a slowing limb, said cam being provided at the inferior cusp adjacent the slowing limb with a rest face and with an upstroke valve-closing limb extending 40 from the rest face to the lifting limb, and said cam being thickened at the superior cusp to form a reversing face and thickened at the inferior cusp to form a node; and means operably connecting the cam to said sucker rods.

In testimony whereof, I have hereunto set my hand at Los Angeles, California this 10th day of July, 1913.

HUDSON F. STORY.
